Application July 15, 1954, Serial No. 443,494

3 Claims. (Cl. 241—40)

This invention pertains to an improved hydrocarbon oil fluid coking process. The present invention also relates to an apparatus and to a process for the comminution of particulate solids. More particularly, this invention is concerned with the preparation of seed coke in a hydrocarbon oil fluid coking system. The present invention involves apparatus for the size reduction of heat-carrying solid particles used in fluid coking processes and also involves a particular processing arrangement for seed coke production, characterized by its practicability and efficiency.

A coking process for pyrolytically upgrading petroleum oils, which utilizes the fluidized solids technique has been recently developed. In this fluid coking process, as is known by the art, a mass of fluidized high temperature solids such as sand, metal particles, spent catalyst, etc. and especially coke particles formed in the process, is used to supply the heat for converting oils. A charging stock to be upgraded is sprayed into the fluid bed and, upon contact with the high temperature solids, undergoes pyrolysis, evolving lighter hydrocarbon vapors and depositing carbonaceous residue, i. e., coke, on the solids. Various solids such as those mentioned above may be used to supply the heat to conversion. However, since coke is a product of the process, this petroleum coke is the preferred contact solids.

Because of the deposition of coke on the particles, the particles increase in size and steps must be taken to counteract this growth. The present invention pertains particularly to a means and a method for controlling the number, the particle size and particle size distribution of the circulating solids, whereby continuous and efficient operation of the coking process is assured.

Charging stocks customarily used in fluid coking operations comprise petroleum tars, cycle stocks, vacuum and atmospheric residua, recycle heavy ends from the coker effluent, and similar high-boiling low value, heavy oils containing constituents non-vaporizable without thermal cracking. Broadly, however, charging stocks suitable for use in a fluid coking process include shale oils, asphalts, tars, coal tars, synthetic oils, extracts, cycle stocks, whole crudes, distillate and residual fractions therefrom, or mixtures thereof.

In most fluidized solids systems wherein a solid is reacted or contacted with a fluid, the solid is usually circulated to an external vessel for regenerative or reheating purposes. In such multi-vessel systems, the necessary driving force for circulating the solids may be created by use of a pressurizing standpipe. In such a standpipe, the solids are conveyed downwardly at relatively high densities until a sufficient fluidstatic head is created to convey the solids. This invention has particular relationship to a fluid coking system of this nature wherein the heat-carrying solids are circulated from the coking vessel to a heating vessel and back through a pressurizing standpipe system.

In fluidized solids systems, it is highly desirable, if not necessary, to maintain an optimum size and size distribu-

tion of the fluidized solids. If the solids are too fine, the solids are readily lost from the system by entrainment in the fluidizing gases. If the solids are too large, fluidization becomes difficult, particularly within the range of fluidizing gas velocities used and proper circulation of the solids is hindered. In hydrocarbon oil fluid coking systems, it is preferred to operate with particles in the size range of about 40-800 microns, although the size of the particles may vary somewhat beyond these limits.

Because of the above-mentioned accretion in the size of the particles, portions of the coke must be withdrawn from a fluid-coking system to maintain the total mass or weight inventory of the solids substantially constant and small size particles must be supplied to the system to keep the numerical inventory of the particles in the system substantially constant. Preferably this withdrawal and addition is done continuously. Experience indicates that the desirable seed coke size is within the range of 100 to 200 mesh. Below this range, particles agglomerate readily and/or are blown from the system and above this range the amount of material that must be passed through the grinding device to maintain a numerical balance of particles in the coking system becomes prohibitive.

25 The prior art has suggested the use of jet attritors or impact grinders to obtain the necessary seed coke production in fluid coking processes.

The jet attrition grinders or impact grinders known by the prior art operate on the principle of accelerating coke particles with a fluid medium, e. g., steam, to a high velocity and discharging the mixture against a stationary target. The impact with the target shatters the particles and yields the desired size reduction. To attain the high velocities necessary for satisfactory grinding, static pressure energy is converted into kinetic energy. It is, therefore, desirable to provide for the maximum pressure drop over the jet grinding means within the limits allowed by the process.

30 The design of the jet attrition apparatus has presented problems. One of the main problems has been rapid erosion of the target surfaces. Another problem is the efficient design of the target surface such that the maximum impacting of the particles is obtained. This invention by a particular jet attriter design admirably solves these problems.

35 It is, therefore, an object of the present invention to devise a process and apparatus for the comminution of particulate solids, particularly of coke particles used in hydrocarbon oil fluid coking systems. Another object is to provide seed coke as growth nuclei in a hydrocarbon oil fluid coking system by jet or impact grinding.

40 A salient feature and object of this invention is to incorporate a jet grinder means within a fluid coking system that makes maximum use of the static pressure differential available. To do this, particulate coke to be reduced in size is withdrawn from the lowermost portion of one of the pressurizing standpipes, as at this point the coke is under the highest static pressure existing within the process. After being reduced in size, the impacted coke is returned to the system to a point having the lowest static pressure. Preferably the coke is returned to the coking vessel above the fluidized bed of solids contained therein. This place of return has a relatively low static pressure and also is chosen for reasons stated below.

45 One of the problems in fluid coking, and in the provision of seed coke therefore, is the loss of fines from the system. As the fluidizing gas passes through the bed of solids, the smaller particles are entrained therefrom and will be lost in the system through the vented gases, particularly with the burner flue gases. This is undesirable, not only because these fines are valuable as seeds,

but also because such losses contribute to atmospheric pollution. By introducing the seed coke into the coking reactor in accordance with this invention, this loss is avoided. The fines are agglomerated on the wet coke particles in the reactor bed and thus are held in the system. Any fines entrained through the reactor cyclones are returned with the stream of recycled heavy ends in a wetted condition.

The nature and objects of this invention will be more fully understood by reference to the attached drawings which form a part of the specification. In the drawings, Figure I diagrammatically portrays a fluid coking system operated in accordance with the teachings of this invention. Figure II illustrates a preferred jet impact grinder used for the production of seed coke. Figure III is a cross-sectional view of the apparatus shown in Figure II taken along line III-III of Figure II.

In brief compass, the present invention proposes an improved hydrocarbon oil fluid coking process which comprises injecting a charging stock into a fluidized bed of particulate solids maintained at a coking temperature in a coking zone to form relatively lighter hydrocarbon vapors and carbonaceous residue which is deposited on the solids causing them to grow in size, withdrawing the vapors overhead as product, withdrawing as product portions of the particulate solids at a rate adjusted to maintain the mass of the solids in the process substantially constant, circulating the particulate solids to an external heating zone and back to maintain the coking temperature, withdrawing a portion of the solids so circulated at a point of relatively high pressure and impelling the withdrawn portion at a relatively high velocity against an impact surface to produce small particles of seed size, and introducing the particles so impacted into the upper portion of the coking zone above the fluidized bed whereby the particle size, particle size distribution and number of the particulate solids in the process are maintained substantially uniformly.

In a preferred embodiment of this invention, the comminution of the solids is accomplished by use of size reduction apparatus of special design which comprises an attriter vessel adapted to contain a moveable target and having an outlet at one end for the discharge of the comminuted coke, a target positioned within the vessel, an acceleration conduit for admitting a high velocity coke-gas suspension into the vessel in the form of a confined stream, the acceleration conduit being radially positioned on the vessel and terminating in spaced relationship to the target, positioning means operatively connected to the target for positioning the target transversely to the acceleration conduit, and mounting means for detachably mounting the positioning means on the other end of the vessel. Preferably the target is an elongated channel-shaped member positioned in such a manner that the confined, high velocity, solids-gas stream strikes substantially perpendicularly the inner bottom of the channel-shaped member.

Referring to Figure I, there is shown schematically a coking process incorporating the teachings of this invention. The art of fluid coking of petroleum oils is generally quite well known and for this reason will be but briefly described, sufficient to create a setting for this invention. The major items of equipment shown in the drawing are a fluid coking vessel 1 with a superposed product quench and separation system, a heating vessel 2 or fluid bed burner, and a jet attriter 3.

An oil to be converted, such as a heavy vacuum residuum, is introduced into the coking vessel by lines 4. A fluid bed of particulate petroleum coke is maintained in the vessel at a temperature in the range of 900° to 1600° F. The residuum is converted to lighter vapors which pass upwardly through cyclone system 5 wherein entrained solids are removed and thence into the quenching and fractionation section of the coker. The vapors issuing from the cyclone system are cooled by descending

liquid to substantially stop further reaction and to condense heavy impurity containing ends. The condensed ends are removed from the tower by line 6, a portion of which are recycled by line 7 to the coker, and another portion is recycled by line 8 through heat exchanger 9 to serve as a quench medium or reflux. The vapors continue upwardly through the tower and further amounts are condensed out. A gas oil portion of the vapor is removed by line 10 as product. A portion of this gas oil is recycled by lines 11 and 12 through heat exchangers 13 and 14 respectively to serve as reflux and to affect staged heat removal. The remaining lighter portions of the coker products are removed overhead by line 15 as product. The coker products can, of course, be subjected to further treatment as desired, e. g., hydroprocessing, stabilization, blending, catalytic cracking, etc.

Steam or other fluidizing gas is admitted to the base of the coker as by line 16 and serves to strip the coke particles before they are circulated to the heater and then serves to fluidize the solids contained in the coker. Large size particles or agglomerates may be formed in the coker and these oversize particles can be removed by line 17.

To maintain the coking temperature, a portion of the coke is continuously circulated through line 18 to an external heating zone, e. g., a fluid bed burner 2, wherein it is reheated to a temperature of about 100° to 300° F. above the coking temperature. The reheated coke is then circulated to the coking vessel from the burner by line 19. The circulated coke descends downwardly through a standpipe in a relatively dense phase condition whereby a fluid static head is created that serves as a driving force and a pressure seal between the vessels, as is well known by the art. Air or another oxidizing gas is admitted to the base of the burner vessel by line 20. This air serves to fluidize the coke therein and supports a partial combustion of the coke. The flue gases formed by the combustion, after having entrained solids substantially removed, are vented overhead from the burner vessel by line 21. Other heating means may, of course, be used to heat the coke including transfer line burners, gravitating bed burners, shot-heating systems, or other direct or indirect heating means.

A net amount of coke beyond that required to supply the necessary heat for the pyrolysis is produced by the process. This coke can be removed as product from the process by line 22. Preferably, this coke is quenched to prevent ignition of it upon contact with the atmosphere. Also preferably, the coke removed as product is elutriated or otherwise classified so that only relatively coarse coke is removed as product. This practice reduces greatly the amount of grinding or size reduction that must be practiced to provide seed coke for the process.

The above-described fluid coking system is exemplary of one in which the present invention has applicability. There is no intent to claim features of fluid coking other than those that necessarily relate to the present invention.

To produce growth nuclei or seed coke, coke is withdrawn from the cold coke standpipe 18 by line 23 and is circulated to the jet attriter. It is preferred to withdraw the attriter feed from the cold coke standpipe in this particular coking process because the pressure at this point exists primarily because of a fluid bed and is relatively constant. A small amount of steam or other aeration gas may be admitted to line 23 by line 24, to facilitate the flow of the coke. The coke is admitted from line 23 into line 25 wherein it is admixed with substantial quantities of a conveying gas, e. g., steam, that serves to accelerate it to a high velocity sufficient to create the kinetic energy necessary for the grinding. The contents of line 25 are then discharged into attriter vessel 3 wherein the high velocity particles are impacted against a target and comminuted. The

operation of attriter vessel 3 is more fully presented hereinafter.

The outlet velocities used in the jet grinder will, of course, vary with such factors as acceleration tube diameter and length, solids loading, target configuration, and particularly the available pressure drop across the grinder. The gas velocities at the outlet may range from 200 to 2,000 ft./sec. with velocities in the range of 200 to 700 ft./sec. being normal and the maximum velocity of the solids may range from 50 to 1000 ft./sec. The higher velocities are used to obtain a finer product as is hereinafter described. The solids loading in the acceleration tube may vary from 0.05 to 5.0 lbs./cu. ft. with 0.2 to 1.0 being preferred. The attriter performance may readily be changed by varying the coke and/or steam rate.

The impacted particles are then transferred from the attriter vessel by line 26 to the coking vessel. As before stated, it is preferred to introduce these impacted particles into the solids disengaging space above the coking bed as this is a zone of low static pressure. This coke may be returned to the burner 2 to avoid condensing with the product vapors, the acceleration steam used in the attriter. However, many of the fines would be blown out of the burner and lost from the system. Steam or other purge gas may be connected to line 26 by line 27. This gas will not necessarily be admitted through this connection during normal operation. During periods when the attriter is not operating, it is desirable to flow gas through line 27 into the coking vessel to prevent coke deposition on the terminating portions of line 26.

It is advantageous in some applications of this invention to elutriate or otherwise classify the material withdrawn from the coke circulation system prior to grinding it. Stated differently, it may be desired to grind only a relatively coarse material and to avoid unnecessary handling of the material already in the desired size range. Thus the contents of line 23 may be elutriated or otherwise classified so that only relatively coarse material is passed to jet attriter 3.

It is also advantageous to provide means for creating a larger pressure differential over the jet attriter vessel than that existing inherently in the process. For example, an aspiration system, i. e., a steam jet ejector, may be inserted in line 26 to supplement the pressure differential existing between the inlet of line 23 and the exit of line 26; or a steam ejector may be inserted at the junction of lines 23 and 25, with the coke being introduced into the low pressure zone of the venturi.

It is desirable in some applications to elutriate or otherwise classify the jet attriter product, i. e., the impacted coke. Thus a cyclone separator, or a dense or dilute phase elutriator using extraneous gas and/or the gas used in the jet grinder, can be inserted in line 26. This is desirable in that the coarse fraction of the jet attriter product will be segregated for recycle to the attriter. It has been found that less power is required to obtain a given size reduction on recycled coke particles as compared to fresh particles.

It is to be understood that the coke feed to the attriter may also be obtained from the lower portion of the standpipe of line 19 as the coke will exist under a relatively high pressure, comparable to the pressure obtained in the standpipe of line 18. As this coke from the burner is at a higher temperature, this will avoid the normal heat load imposed on the coker because the jet attriter product will be returned to the coker at about the temperature of the coker. Further, in some applications, it may be desired to supply coke to the attriter through a pressurizing standpipe other than those used to circulate coke between the coker and burner. If an extra standpipe be used, it can be of sufficient height to provide a high fluidic pressure. The use of such an extra standpipe is particularly desirable when

boiler fuel is produced by the attriter, as hereinafter described.

Other similar variations of the processing sequence of this invention will be apparent to those skilled in the art. Suitable instrumentation may be used in the practice of this invention without departing from the spirit thereof.

With particular reference to Figure II and III, a preferred jet attrition mechanism suitable for use in the practice of this invention will be described. A channel shaped target surface 30 is positioned within the attriter vessel 3. The coke particles along with the conveying steam are admitted into vessel 3 through an acceleration conduit tube or tube 31. The acceleration tube is detachably mounted in a radial position in attriter vessel 3 by flanged nozzle 42 and terminates in spaced relationship to the target surface 30. The spacing of the tube from the target has not been found to be critical. For commercial size pipe of about 1 to 8 inches diameter, an acceleration tube of about 1 to 6 feet long can be used. A 2 foot long tube has been found to be an optimum length and is preferred. As the tube increases in diameter, longer lengths may be used.

There is inserted in line 25, that conveys the high velocity particles to the jet attriter, a spool piece 32. This spool piece is readily replaceable. By inserting various lengths, the spacing of the acceleration tube to the target surface can be readily varied. This also allows removal and inspection of the acceleration tube and allows the insertion of acceleration tubes of different lengths and internal diameters. The use of this spool piece also permits the jet attrition mechanism to be readily adapted to widely varying operating conditions.

The particular design of target 30 is another feature of this invention. The narrow elongated shape of the target permits the use of a relatively small aperture in the attriter drum for inserting the target. This permits the use of relatively inexpensive manholes in the drum to withstand the pressure. The channel shape of the target is particularly advantageous in that it provides for maximum and efficient impacting of the coke particles. This shape minimizes collisions of particle on particle and provides a ready exit for the impacted particles upwardly and downwardly from the impact surface. The particles emerging from acceleration tube 31 have a line of flow as indicated by directional lines 33. Other elongated target shapes can, however, be used in the practice of this invention, including flat plates and bars. Other forms of multiple collision targets may also be used.

The impacted particles flow downwardly through the attriter vessel and are removed from the vessel through outlet 26, the accelerating gas being used to convey the particles.

A special feature of this invention is that the target surface 30 is made to move transversely to the axis of the acceleration tube in such a manner that a large target surface is available. This allows maximum continued use of the jet attriter by minimizing cessation of operation to replace the target and also promotes the efficiency of grinding. It has been discovered that even with the best alloy steels available, the target wear rate is about 0.001 to 0.008 lb./ton of seed coke product produced.

It has also been discovered that movement of the target surface is desirable in that it inhibits the formation of concave target surfaces. When a concave surface is presented to the high velocity stream, attrition efficiency decreases because the impacted particles rebound inwardly and form a cushion. Also it is probable that a concave surface allows oblique impact of the particles such that the energy of the particles is only partly dissipated on the initial impact. It is to be appreciated, therefore, that this feature of a movable target is essential to practical operation of the jet attriter.

In operation, the target surface is periodically or continuously varied by moving target 30 transversely past

the axis of acceleration tube 31 substantially parallel to the axis of accelerating vessel 3. This motion may, of course, be imparted by manual or mechanical means. Thus an air or electric motor driven worm gear may be used to position the target surfaces. As shown, however, a manual system is used to position the target. A mounting conduit 35 is superposed upon attriter vessel 3. A support bracket 36 is affixed to the mounting conduit and supports a drive shaft capable of reciprocating motion. The drive shaft 37 is affixed to one end of the target member and passes upwardly through the upper portions of the mounting conduit. A sealing arrangement, i. e., a stuffing box 38, is used to secure a substantially gas-tight seal between the moving driving shaft and the stationary parts of the attriter. The upper portion of the driving shaft is threaded. The threads engage a crank or handwheel 39, the handwheel being used to impart the desired motion to the drive shaft. There is shown a simple instrumenting device to indicate the position of the target surface relative to the acceleration tube. The indicator consists of a pointer 40 affixed to the driving shaft and a prepositioned, marked plate 41.

The following example is given as a specific illustration of this invention, but the invention is not to be limited thereby. A fluid coker similar to the one depicted in Figure I may operate at a coking temperature of 950° F. with a pressure in the solids disengaging space, before the cyclones, of 11 p. s. i. g. A coke inventory of 70 tons may be used. The burner temperature may operate at 1125° F. The coke circulation rate to the burner is, under these conditions, about 4.3 tons/minute. With such size of equipment, the fresh feed is introduced into the coker at the rate of about 3800 B/SD, if the feed has a preheat of 700° F. and inspections of 1.9 °API gravity and 30 wt. percent Conradson carbon.

For this feed, approximately 240 tons of coke/day is produced and 197 tons per stream day is removed as net coke product.

In the standpipe conveying the coke from the fluid coker to the burner, at the point where the attriter feed is withdrawn, there exists a pressure of approximately 30 p. s. i. g. and the coke-gas suspension has a temperature of 950° F. and a density of 45 lbs./cu. ft. To maintain the balance of coke particle, number and size distribution, approximately 350 tons/day is circulated to the jet attriter. Approximately 2 S. C. F. of 90 p. s. i. g. steam is admixed with the coke sent to the attriter/lb. of coke. With an acceleration tube having an I. D. of 2.32 inches and a length of 2 feet, the maximum velocity of the coke particles is 200 ft./second and the gas velocity is 600 ft./second with a pressure drop of about 15 p. s. i. over the tube. The spacing of the acceleration tube from the target surface is about 6 inches with a target of 10" x 5" channel, 1" thick. The impacted coke is circulated from the attriter at a density of about 0.5 lb./cu. ft. and a velocity of about 60 ft./sec.

For the above specified conditions, the size and size distribution of the various coke streams is given in the following table I. The table indicates the size of the circulating coke stream in the system (which includes a feed to the attriter vessel), of the product produced by the attriter, and of the net product coke removed from the process. The net process coke is classified so that only relatively coarse material is removed as product.

Table I

Wt. Percent Smaller than—	Circulating Coke	Attriter Product	Net Product of Process
800 microns.....	99	100	97
400 microns.....	95	98	91
295 microns.....	81	84.5	55
246 microns.....	46.0	54.0	25
175 microns.....	12.0	25.5	7
147 microns.....	6.5	14.5	3
74 microns.....	0.3	2.3	0

An attractive alternative method of practicing this invention is to operate the jet attriter at high severities to produce a relatively fine attrited product. The finer portion of the attrited material can then be removed as net product. In this way, a coke product is produced that is suitable as a fuel in boilers or furnaces. Thus sufficient steam may be used to accelerate the coke particles to relatively high velocities in the range of 1000 f./s., to 2000 f./s., e. g., 1500 f./s. This will produce an attriter product having a substantial portion of material smaller than about 200 mesh. If high severity grinding be practiced, then the attriter product would be classified as by elutriation, cyclone separation, screening, etc., to attain this fine size material as net product coke of the process. The intermediate size fraction from the attriter can be circulated to the coker as seed coke and as a further alternative the coarser material may be recycled to the attriter for further treatment.

Having described the process and apparatus of this invention, what is sought to be protected by Letters Patent is succinctly set forth in the following claims.

What is claimed is:

1. Apparatus for the size reduction of particulate coke which comprises an attriter vessel adapted to contain a movable target and having an outlet at the bottom for the discharge of comminuted coke, an elongated channel-shaped movable target member positioned within said vessel, an acceleration conduit terminating in spaced relation to said target member for admitting a high velocity coke-gas suspension into said vessel in the form of a confined stream, said acceleration conduit being radially positioned in said vessel in such a manner that said confined stream strikes substantially perpendicularly the inner bottom surface of said target member, positioning means operatively connected to said target member for positioning said target member transversely to the axis of said acceleration conduit, and mounting means for detachably mounting said positioning means on the top of said vessel.
2. The apparatus of claim 1 wherein said positioning means includes a manually operated shaft attached to said target member.
3. Apparatus for the comminuting of particulate solids which comprises, in combination, an elongated cylindrical attriter vessel with a bottom outlet for the discharge of comminuted solids, a relatively narrow elongated movable target positioned within and parallel to the axis of said vessel, an acceleration conduit radially positioned on said vessel terminating in longitudinal spaced relation along the axis of said acceleration conduit to said target for admitting a confined high velocity solids-gas stream substantially perpendicularly to said target for positioning said target transversely to the axis of said acceleration conduit, and mounting means for detachably mounting said position means on the top of said vessel.
